EDGE SETTING AND INKING MACHINE

George W. Liberty and Gustaf Bratt, Lynn, Mass.,
assignors to National Development Company,
Lynn, Mass., a corporation of Massachusetts

Application November 9, 1939, Serial No. 303,630

4 Claims. (Cl. 12—42)

This invention relates to machines for finishing the edge of shoe treads, such as the edge of a toplift of a wood heel.

In finishing the edge of shoe treads, the edge is inked and waxed and then set to form a finishing bead along the tread portion. Machines have been provided for setting the edge of the tread portion of a shoe, but prior to the present invention, the inking operation has been performed by hand. Thus, the edge of each tread portion has been inked and waxed by a hand operation and thereafter has been set by machine.

It is an object of the present invention to provide a suitable machine for performing the inking and waxing operation upon the edge of the tread portion of a shoe.

The invention will be more clearly understood from the following description in conjunction with the accompanying drawings, in which,

Fig. 1 is a side elevational view of a machine embodying the invention;

Fig. 2 is a plan view of the same looking in the direction of the arrow in Fig. 1;

Fig. 3 is a view similar to Fig. 1, showing the waxing and inking mechanism detached;

Fig. 4 is a sectional view taken on the line 4—4 of Fig. 2;

Fig. 5 is a plan view looking in the direction of the arrow in Fig. 3;

Fig. 6 is a perspective view of a wood heel showing the edge of the toplift after it has been waxed or inked by the machine of the invention;

Fig. 7 is a perspective view of a wood heel showing the edge of the toplift set by the machine of the invention;

Fig. 8 is a side elevational view of a portion of the machine; and

Fig. 9 is a view similar to Fig. 3 showing the parts in different positions.

The machine illustrated in the accompanying drawings embodies the essential elements of that described in the patent to Merton W. Howard, No. 1,829,800, dated November 3, 1931, which is arranged to roll in a joint *a* between the heel *A* and the toplift *B* (Fig. 7), and to form a bead *c* along the curved part of the toplift at its outer edge. In addition, the machine embodies other instrumentalities which function in timed relation to the edge setting mechanism for first inking the edge of the tread portion.

As illustrated in the accompanying drawings, particularly Figs. 1, 2, 3 and 4, the machine of the invention comprises a frame 20 which is designed to provide the necessary bearings, sup-

ports and guides for the various parts. A main driving shaft 27 is journalled in bearings in the frame 20 and is driven from a suitable source of power (not shown). Fast upon the shaft 27 is 5 a pinion 30 which meshes with a gear 31 on a cam shaft 32 journalled in suitable bearings in the frame 20. Journalled respectively in bearings 33 and 34 in the frame 20 are the aligned sections 35 and 36 of a two-part jack shaft, the 10 ends of said sections being spaced from one another and being connected by a yoke 37. The yoke 37 is formed at one end with a hub 38 keyed or otherwise fixed to the end of the shaft section 35, and its opposite end with a split hub 39 abutting the bearing 34 and secured to the end of the shaft section 36 by a clamp bolt 40 and spline (not shown), thereby permitting longitudinal adjustment of the shaft section 36 in the hub 39.

Secured to one end of the main driving shaft 20 27 is a crank arm 42 having ways to receive a slide 43 adjustable therein by means of an adjusting screw 44. Pivoted to the slide 43 is one end of a pitman 45 the opposite end of which is pivoted to a block 46 slidable in a slot 47 in a gear segment 48 pivoted at 49 to the frame 20 and meshing with a pinion 50 secured to the outer end of the section 35 of the jack shaft. The block 46 is normally held in the upper end of the slot 47 to afford the driving connection between the pitman 45 and segment 48, by means of a dog 51 pivoted at 52 to said segment and normally held in operative position by a spring 53. The dog 51 is formed with a foot 4 which depends into the path of movement of a pin 55 30 projecting from the face of the gear 31 which thereby constitutes a controller for said dog.

It will be seen that with the block 46 locked in its operative position in the slot 47, the jack shaft and work holder will be oscillated from the main 40 driving shaft 27 through the crank 42, pitman 45, segment 48, and pinion 50, the amplitude of oscillation being determined, in accordance with the 45 particular style of toplifts to be operated upon, by adjustment of the slide 43. After one revolution of the gear 31 which may be designed to correspond to any desired number of oscillations of the jack, the foot 4 is engaged by the 50 pin 55, causing the dog 51 to be disengaged from the block 46 leaving the latter free to reciprocate in the slot 47. The jack, therefore, will remain idle during one complete rotation of the shaft 27, this being the unloading and loading period in 55 the cycle of operations of the machine during

which period one completed piece of work is removed from the machine and a new piece inserted. By the time shaft 27 has completed one revolution, the pin 55 has moved out of engagement with the foot 4, permitting the spring 53 to restore the dog 51 to its normal position, thereby again locking the slide 46 to the segment 48, and the oscillation of the jack is resumed or continued.

The means for positioning and clamping the work in the jack comprises a toplift rest or plate 56 for engaging the outer face of the toplift B, a breast gauge 7 for engaging the breast of the heel A, a heel seat support 58 carrying a detachable positioning plate 59 for engaging the heel seat portion of the heel A.

The breast gauge 7 has a shank portion slidably received in the yoke 37 and suitably secured for adjustment therein, the means for adjusting not being shown. The breast gauge 7 positions the heel horizontally and its adjustment adapts the machine to heels of varying shapes in order that the axis of the curvature of the toplift edge may substantially coincide with the axis of oscillation of the jack, that is to say, the common axis of the shaft sections 35 and 36. The vertical positioning of the heel in order to bring said axis substantially into coincidence in the vertical plane is effected by the sense of touch of the operator with the assistance of the heel seat centering plate 59 which is detachably secured to the heel seat support 58. The machine is provided with mechanism, not shown, for drawing the opposed clamping devices apart to permit the insertion of the heel.

A lever 75 (Figs. 1, 2 and 10) is pivotally mounted at 76 to the frame 20. The lever 75 is provided with a pair of spaced lateral projections 77 between which a rod 78 extends. An arm 79 is pivotally mounted upon the rod 78 and carries a holder 80 in which the edge-setting iron 8 is mounted. The iron 8 may be heated electrically by means indicated at 74. An adjusting screw 81 is threaded in the arm 79 and is adapted to engage the surface of the lever 75. One end of a coil spring 65 is secured to a hook 66 fixed in the arm 79 and the other end of the spring 65 is secured to one arm of a bell crank 90 which is pivotally mounted at 91 to the frame 20. The other end of the bell crank 90 carries a follower roll 92 engaging a cam 93 fixed upon the cam shaft 32. The spring 65 serves to maintain the screw 81 (Fig. 2) in engagement with the arm 75 and is adapted to cause the iron 8 to exert a heavy pressure upon the work. A short lever 83 (Fig. 8) is pivotally mounted intermediate its ends upon a stud 84 fixed in the lever 75. A stud 85 projecting laterally from near one end of the lever 83 carries a follower roll 86 engaging a cam 87 fixed upon the cam shaft 32. A hook 88 is fixed to the lever 83 near its other end and is adapted to receive one end of a coil spring 89, the other end of which is secured to the frame 20. The spring 89 maintains the opposite end of the lever 83 in engagement with the end of an adjusting screw 94 threaded in a lug projecting from the lever 75 and also causes the iron 8 to exert a light pressure upon the work.

A reservoir 100 (Figs. 3 and 9) adapted to receive colored wax or ink is mounted upon a bracket 101 fixed to the frame 20. If a colored wax is employed which is solid at normal temperatures, it may be liquefied by electrically heating

means 10. An ink supply roll 11 is fixed upon a shaft 102 mounted for rotation in suitable bearings in the wall of the reservoir 100. Heating means 13 is provided for electrically heating the roll 11. A pulley 103 is fixed upon the shaft 102 and is connected by a belt 104 with a pulley fixed upon the cam shaft 32. The roll 11 is positioned in a plane spaced from the plane in which the tool 8 is moved toward and away from the work.

10 A shaft 116 is mounted for rotation in suitable bearings in the frame 20. An arm 110 is fixed to the shaft 116 near one end thereof and carries a roll 111 adapted to engage a cam 112 fixed upon the shaft 32. The roll 111 is maintained in engagement with the cam 112 by a spring 117, one end of which engages a hook fixed in the arm 110 and the other end of which is secured to the frame 20. A sleeve 113 is slidably keyed upon the shaft 116 near its other end and is provided with an annular groove 114. An arm 119 is pivotally mounted upon the frame 20 and is provided with a fork 118 which straddles the sleeve 113. Wear resisting shoes 115 are pivotally mounted on the opposite arms of the fork 118 and engage the groove 114. A stud 121 is fixed in a lug projecting laterally from the arm 119 and carries a roll 122 positioned in the groove on the periphery of a cam 123 fixed upon the shaft 32.

15 The sleeve 113 is provided near one end with a radial projection 125, one face of which is provided with a recess 126. One end of an arm 127 projects into the recess 126 and is pivotally mounted upon a stud 128. Leaf springs 130 and 131 are fixed upon opposite edges of the arm 127 and project into the recess 126 between the ends of adjusting screws 132 and 133, which are threaded in the projection 125. An ink-transfer roll 14 is pivotally mounted upon the arm 127 near its other end and is adapted to be moved by the mechanism described between a position engaging the roll 11 and a position engaging the edge of the toplift B. Means generally indicated at 15 is provided for heating the roll 14.

20 During the unloading and loading period in the cycle of operations of the machine, as previously described, the oscillation of the jack is stopped so that one completed piece of work may be removed and a new piece inserted. At this time the iron 8 is retracted from the work to the position shown in Fig. 1 and the ink-transfer roll 14 is in the dotted line position shown in Fig. 3 with its periphery engaging the periphery of the ink supply roll 11. Near the end of the loading period, the cam 123 (Fig. 5) causes the arm 119 to swing and slide the sleeve 113 along the shaft 116. At the same time, the cam 112 (Fig. 3) swings the arm 110 to rotate the sleeve 113 and swing the arm 127. As a result of the combined action of the cam 123 and the cam 112, the roll 14 is moved in a diagonal path from its dotted line position to its full line position shown in Figs. 3 and 5. The jack then starts its oscillation and, as it moves from one end of its amplitude of movement to its other end, ink is applied by the roll 14 to the edge of the toplift B. As the jack completes its other half of one oscillation, the cams 123 and 112 cooperate to move the roll 14 from its full line position shown in Fig. 3 to its dotted line position. At the same time, the cam 87 permits the spring 65 to swing the arm 75 so as to move the iron 8 from the position shown in Fig. 1 to a position engaging the edge of the top lift B. The jack then completes its cycle of oscillations

and the iron 3 sets the edge of the toplift B. The oscillation of the jack then stops to permit unloading of the completed piece of work and the insertion of a new piece. The iron 3 then is moved from its position engaging the edge of the toplift to its inoperative position as shown in Fig. 1.

The ink used in the preferred practice of the invention is a colored wax compound which is solid at normal temperature. It is liquefied by heat and applied while in its heated liquid state and dries and hardens almost instantly after application to the edge of the tread. Throughout this specification and appended claims the term ink is intended to mean either a wax or color or both.

I claim:

1. In a machine for finishing the edge of a portion of a shoe tread, such as the edge of a toplift attached to a heel, means for holding said tread, an edge setting iron, means for applying ink to said edge, means for moving said applying means from an operative position engaging said tread to an inoperative position while moving said iron from an inoperative position to an operative position engaging said tread, and means operative when said iron and said applying means are in their operative positions for causing relative movement between the same and said holding means whereby to ink and set the edge portion of said tread.

2. In a machine for finishing the edge of a portion of a shoe tread, such as the edge of a toplift attached to a heel, means for holding said tread, an edge setting iron, means for applying ink to said edge, means for moving said

applying means from an operative position engaging said tread to an inoperative position while moving said iron from an inoperative position to an operative position engaging said tread, and means for oscillating said holding means.

3. In a machine for finishing the edge of a portion of a shoe tread, such as the edge of a toplift attached to a heel, means for holding said tread, an edge setting iron, an ink reservoir, an ink supply roll depending into said reservoir, means for rotating said roll, a transfer roll, means for moving said transfer roll into and out of positions engaging said ink supply roll and said tread, means for moving said iron between an operative position engaging said tread and an inoperative position, and means for oscillating said holding means.

4. In a machine for finishing the edge of a portion of a shoe tread, such as the edge of a toplift attached to a heel, means for holding said tread in a fixed location, means for applying ink to said edge, means for moving said applying means from a position in engagement with said tread in said fixed location to a position out of engagement with said tread, an edge setting iron, means for moving said iron from a position in engagement with said tread in said fixed location to a position out of engagement with said tread, means for relatively moving said tread and applying means to cause the latter to ink said edge, and means for relatively moving said tread and iron to cause the latter to set said edge.

GEORGE W. LIBERTY.
GUSTAF BRATT.
